UNITED STATES PATENT OFFICE.

OTTO A. GERDES AND EMIL GUTH, OF BLUE ISLAND, ILLINOIS.

SPARK-INTENSIFIER.

1,365,168.

Specification of Letters Patent. Patented Jan. 11, 1921.

Application filed May 26, 1920. Serial No. 384,486.

To all whom it may concern:

Be it known that we, OTTO A. GERDES and EMIL GUTH, citizens of the United States, residing at Blue Island, in the county of 5 Cook and State of Illinois, have invented certain new and useful Improvements in Spark-Intensifiers, of which the following is a specification.

This invention relates to a spark intensifier and aims to provide a device of that character adapted especially for use upon old or worn spark plugs to renew the life and efficiency thereof and to intensify the spark upon new spark plugs.

10 15 A further object of the invention is the provision of a spark intensifier of extremely simple construction so that the same may be cheaply manufactured and will serve the purposes in a thoroughly practical and 20 efficacious manner.

A still further object of this invention is to provide a spark intensifier that forms a gap over which the spark will jump for intensifying same, said gap having a plurality of teeth upon each side so as to 25 greatly increase the efficiency of the device.

With the above and other objects in view this invention consists of certain novel combinations, arrangement and construction of 30 parts as will be hereinafter more fully described and claimed.

In the accompanying drawings:—

Figure 1 is a top plan view of my invention,

35 Fig. 2 is a side elevation of my invention, and

Fig. 3 is a transverse section taken through our invention.

By referring to the accompanying drawings by numerals, it will be seen that in trying out the invention, there is provided an elongated strip 1, of fiber or other suitable insulating material having apertures adjacent each end for a purpose to be hereafter 45 brought forth.

Situated about this strip 1 we have provided a pair of casings 2 which surround the strip 1 so as to leave a gap 3 therebetween. Bordering upon this gap 3 it will 50 be seen by referring especially to Fig. 1 of the drawing that we have provided a plurality of teeth 4. Each of the casings 2 is provided with apertures 5 registering with the apertures provided in the strip 1.

55 In using this device, it will be seen that

the spark plug indicated in dotted lines in Fig. 2, is provided with a stem extending through one set of the apertures while at the other end of the strip 1 and the other casing 2 we have provided a screw 6 having 60 a head at one end and threads at its other end for receiving the nut 7 whereby the connection 8 may be electrically connected with the adjacent housing 2. Thus the current will be passed from the source to the spark 65 plug as is usual in internal combustion engines.

The above description of our invention refers to the preferred embodiment thereof but it will be readily seen that many 70 changes in the construction of parts and shapes thereof may be made without departing from the scope of the appended claims.

Having thus fully described the invention 75 what is claimed as new is:—

1. As a new article of manufacture, a spark intensifier comprising an elongated insulating strip having apertures adjacent each end, a pair of casings situated upon said strip and provided with apertures adapted to register with the apertures in said strip and situated so as to provide a gap therebetween. 80

2. As a new article of manufacture, a 85 spark intensifier comprising an insulating strip having apertures in each end, casings situated upon said strip so as to leave a gap between the casings, said casings provided with teeth adapted to border on said gap. 90

3. As a new article of manufacture, a spark intensifier comprising a strip of insulating material having apertures in each end, a pair of similarly formed casings provided on said strip and having apertures 95 adapted to register with the apertures in said strip, said casings situated so as to provide a gap therebetween and having teeth bordering on said gap and means provided in one set of said apertures for connecting 100 said device to the source of electrical current.

In testimony whereof we affix our signatures in presence of two witnesses.

OTTO A. GERDES.
EMIL GUTH.
